TAPING AND SEAM PRESSING MACHINE

John M. Calder, Lynn, Mass., assignor to Boston Machine Works Company, Lynn, Mass., a corporation of Massachusetts

Application September 25, 1945, Serial No. 618,498

7 Claims. (Cl. 12—59.5)

1

This invention relates to a machine for taping and pressing a seam in an article such as the quarter of a shoe. The quarter portion of a shoe upper is customarily made by stitching together two pieces of leather, the line of stitching becoming the back seam of the quarter. The line of stitching is run along the margin of the two leather pieces close to the edge, this edge being arcuate in form. The two pieces of leather are inside out when the stitching is done, the quarter being thereafter reversed before being incorporated in the upper of a shoe. The present invention has to do with a machine for facilitating the application of an adhesive tape to the seam on the inside of the quarter and for pressing the seam after the tape has been applied so as to flatten out the interior ridge initially formed by the seam within the quarter.

The invention is shown as embodied in a machine having an anvil and a presser with complementary surfaces, the presser being brought into pressing relation with the anvil after the quarter has been placed upon the anvil so that the seam is received in a transverse groove. The anvil is so constructed that when the presser bears upon it, the bottom surface of the groove moves into flush relation with the adjacent surfaces and the seam is strongly pressed so as to be well flattened. The machine is also provided with a guide element adapted to present the end of a tape which is adhesively coated on one face for convenient application to a quarter to be pressed. A tape feeding means is also provided on the machine to save the operator from the necessity of pulling the adhesive tape from the supply roll.

Other features of the invention will be apparent from the following description of an embodiment thereof and from the drawings, of which:

Figure 1 is a side elevation of a machine embodying the invention;

Figure 2 is a section on the line 2—2 of Figure 1;

Figure 3 is a section on the line 3—3 of Figure 1;

Figure 4 is a fragmentary front elevation of the upper portion of the machine;

Figure 5 is a perspective view of a shoe quarter which has been operated upon by the machine;

Figure 6 is a section on the line 6—6 of Figure 4;

Figure 7 is a section on the line 7—7 of Figure 9;

Figure 8 is a section on the line 8—8 of Figure 10;

2

Figure 9 is a section on the line 9—9 of Figure 7;

Figure 10 is a section on the line 10—10 of Figure 8.

A bench type of machine is illustrated in Figure 1, this machine comprising a frame consisting of a base 20, a short standard 22, and a pair of fixed jaws 24 and 26. The lower jaw 24 is provided with an anvil 30 which is removable and replaceable by anvils of other sizes or shapes. The anvil 30 is made with an arcuate top surface 32 shaped to fit the rear portion of a shoe upper such as that shown in Figure 5. As indicated in Figure 9 the anvil 30 is preferably made with a central 10 shallow groove 34 extending across the upper surface thereof from front to rear. This groove may conveniently be formed by elevating two side blocks 36 and 38 of the anvil slightly above a narrow fixed central portion 40, the top surface 15 of which is the bottom of the groove 34. The side blocks 36 and 38 which flank the central portion 40 are preferably spring pressed upward but can be pressed down so that their upper surfaces are flush with the upper surface of the middle 20 portion 40, these three upper surfaces then forming a continuous rigid surface. Suitable springs 25 42 and 44 may be provided as shown in Figure 9 to maintain the blocks 36 and 38 resiliently raised until pressed down as hereinafter described. As 30 shown, the springs 42 and 44 surround portions of the bolts 46 and 48, the heads of which are adapted to limit the extent of permissible upward movement of the blocks 36 and 38 and thus to define the raised positions of these blocks. If 35 desired, the anvil may be heated by the provision of heating elements 50 and 52 in the blocks 36 and 38 or elsewhere.

A presser 54 is carried by the upper jaw 26 and is movable vertically to and from pressing engagement with the anvil 30. The under surface of the presser 54 is concave so as to be complementary to the convex pressing surface of the anvil 30. The pressure 54 may be operated by any suitable mechanism, mechanical, hydraulic, magnetic, or 45 otherwise. By way of example, a simple mechanical means for operating the presser is indicated in Figure 1. This comprises a walking beam 56 rockably mounted at 57 on the jaw 26. The beam is connected at one end to a shank or rod 58 50 extending up from the presser, and at the other end to a link 60 at the lower end of which is a cam follower 62 riding on the edge of a cam 64. The cam is mounted on a shaft 66 on which is loosely mounted a pulley wheel 68 constantly 55 driven by a belt 70 from a suitable source of power.

(not shown). A one-revolution clutch mechanism indicated at 72 is provided to connect the pulley wheel 68 to the shaft 66 to drive the shaft 66 through one revolution each time the clutch is thrown in by actuation of the control rod 74 which leads to a treadle or the like (not shown).

Also mounted on the shaft 66 is a feed wheel 76 which cooperates with a similar idle wheel 78 to feed a strip of tape 80 from a roll 82 of tape. The roll is on a suitable bracket 84 having a pair of guides 86 to hold it in place. The tape is preferably of woven fabric or other strong material coated on one side with a strong adhesive. The feed rolls 76 and 78 draw a length of tape from the roll each time the machine is operated to maintain a loop 87 of slack tape handily available, the amount thus drawn being sufficient for one application to a shoe quarter. The surfaces of the rolls 76 and 78 are preferably corrugated or knurled to provide an adequate grip on the tape which is being fed. The idle roll 78 is pressed against the roll 76 by a spring 88.

On the front face of the lower jaw is mounted a guide member 90 under which the tape 80 extends so that its free end is presented at a point adjacent to the forward edge of the pressing surface 32 of the anvil 30. Between the guide 90 and the pressing surface of the anvil a presser foot 92 bears against the surface of the jaw or anvil, this foot being supported by the upper jaw 26 and downwardly pressed by a suitable spring 94. The presser 54 is provided with a knife blade 96 on its forward face, this blade projecting sufficiently below the pressing surface of the presser 54 to cut off the tape 80 when the presser descends into a pressing engagement with the anvil 30.

In using the machine the operator grips a shoe quarter which has been turned right side out and applies the leading edge of the quarter at the seam to the free end of the tape 80 adjacent to the forward edge of the anvil. The tape is presented by the guide 90 in proper position for engagement with the quarter, the seam of which is progressively brought into contact with the tape. For this purpose, the tape is arranged at the guide 90 with its sticky side uppermost. When the leading edge of the quarter is applied to the free end of the tape, it adheres thereto and the quarter and tape are pushed toward the rear by the operator so that the quarter becomes progressively cemented to the tape along its seam as the quarter and tape are pushed across the anvil with the seam in the groove 34. When the quarter has been pushed so that its leading edge is at or near the rear edge of the anvil and the entire length of the seam is directly over the groove 34, the clutch 72 is engaged to cause a single revolution of the shaft 66 together with the cam 64 thereon. As is evident from the shape of the cam illustrated in Figure 1, this revolution results in the presser 54 being pressed against the anvil so as to depress the blocks 36 and 38 as shown in Figure 10 and thus to flatten the seam and the tape thereon. The cam 66 maintains the presser and anvil in pressing engagement for an appreciable period of time depending upon the rate of rotation of the shaft 66, during which interval of time the heat and pressure of the anvil serve to set the adhesive on the portion of the tape which is in contact with the quarter. When the presser 64 descends, the knife 96 cuts off the portion of the tape which has been applied to the seam of

the quarter, thus forming a new free end to be applied to the next quarter which is brought for pressing.

I claim:

1. A machine for taping and pressing shoe quarters, comprising a frame, an anvil on said frame having a convex face adapted to receive and support the rear portion of a shoe counter, said anvil having a fixed narrow central portion the top surface of which is offset below adjacent movable portions to form a shallow groove extending across said face, means on said frame presenting the end portion of a tape at a point adjacent to an end of said groove, a presser member supported by said frame above said anvil, said presser member having a concave face complementary to the convex face of the anvil, and means for moving said presser into pressing engagement with said anvil so as to cause relative movement between the portions of the convex face to eliminate the offset between said portions during the pressing engagement.

2. A machine of the class described comprising an anvil having a fixed transverse central portion and flanking portions resiliently supported with their top surfaces higher than that of the central portion to form a shallow groove, said flanking portions being movable to a position flush with the top surface of the central portion, a presser movable to engage said anvil and bring the surface portions into flush relation, and means on said anvil for presenting the end of a strip of tape at one end of said groove.

3. A machine of the class described comprising an anvil having a pressing surface, a presser having a complementary pressing surface movable into pressing engagement with said anvil, a tape guide on said anvil near said pressing surface, and a spring-pressed foot engaging the anvil between the pressing surface and the guide.

4. A machine of the class described comprising an anvil having a pressing surface, a presser having a complementary pressing surface movable into pressing engagement with said anvil, driving means including a one-revolution clutch for said presser, tape feeding means operated by said driving means, a tape guide adjacent to the pressing surface of said anvil, and a spring-pressed foot engaging the anvil between the pressing surface and said guide.

5. A machine of the class described comprising an anvil having a pressing surface, a presser having a complementary pressing surface movable into pressing engagement with said anvil, a support for a supply of tape, a tape guide on said anvil near said pressing surface, and a means carried by said presser for cutting tape on the anvil when the presser moves into engagement with the anvil.

6. A machine of the class described comprising a frame having a pair of fixed jaws, an anvil removably mounted on the lower jaw, a presser member movably supported by the upper jaw, means on said frame for moving said presser to and from pressing engagement with said anvil, a tape feeding means on said frame, a tape guiding means on said anvil, and a spring-pressed foot supported by the upper jaw and pressing against the anvil adjacent to the tape guide.

7. A machine of the class described comprising an anvil having a pressing surface, said anvil having a narrow transverse fixed portion and a spring-raised portion on either side of the fixed portion forming therewith a shallow transverse groove, heating means in said anvil, and a re-

ciprocable presser movable into pressing engagement with said anvil, and means for moving said presser to engage said anvil and to press said raised portions down flush with the fixed portions of the anvil.
